UNITED STATES PATENT OFFICE.

JAMES W. DAWSON, OF CHICAGO, ILLINOIS, ASSIGNOR TO JAMES A. HEDGES AND HOWARD E. HEDGES, FORMING THE COPARTNERSHIP OF J. A. HEDGES & COMPANY, OF CHICAGO, ILLINOIS.

WINDOW-SHADE ADJUSTER.

Application filed May 21, 1923. Serial No. 640,385.

To all whom it may concern:

Be it known that I, JAMES W. DAWSON, a citizen of the United States, residing at Chicago, in the county of Cook and State 5 of Illinois, have invented a new and useful Improvement in Window-Shade Adjusters, of which the following is a specification.

My invention relates to an improvement in window-shade adjusters, in which the 10 use of cords, pulleys, or other means of non-durable character and subject to impairment by wear, is avoided and stable and durable means are provided to be operated by merely turning a handle in conveniently 15 accessible position for the shade-adjusting purpose.

In the accompanying drawings—

Figure 1 is a view in elevation showing a window equipped with my shade-adjusting 20 invention in its preferred embodiment.

Figure 2 is an enlarged broken section on line 2—2, Figure 1;

Figure 3 is a broken section taken at the 25 line 3 on Figure 2;

Figure 4 is a broken and partly sectional view of the upper roller of my improved device, showing it to be formed, as preferred, of telescoping sections;

Figure 5 is a section on line 5—5, Figure 30 4, and

Figure 6 is a section on line 6—6, Figure 2, showing both of the sheathed spiral side-members of my shade-carrying and adjusting equipment.

The following description refers to my 35 device in its operative position:

To the inner faces of the opposite sides of a window-frame 7 are secured, to extend 40 vertically thereon, the respective sheathing tubes 8 and 9, each closed at its lower end and having its upper end surmounted by a box-like housing 10 provided with a flange or attaching element 11, through which it is fastened in place to the frame 7, as are 45

the caps 11^c at the lower ends of the vertical tubes through the flanges or attaching elements 11^a. Similar spiral shafts 12 of rod or wire material as shown, rotatable in the tubes, have their upper ends fastened to 50 the stems or stub shafts 13^a of miter-pinions 13, journaled in suitable bearings 11^b which are the lower walls of housings 10 and which at the zones of contact with tubes 8 interfit into the latter, as shown in Fig. 3. The

lower end of the spiral in the tube 9 is 55 fastened to a stud or stub shaft 14 journaled in the cap thereon (Fig. 1). The lower end of the spiral in the tube 8 is fastened to the end of a stem or drive shaft 15 journaled in the adjacent cap and extending at its 60 lower end through the top of a housing 10^a, wherein it carries a miter-pinion 13, this housing being also secured in place on the lower part of the window-frame through a flange 11^a. A miter-pinion 13, to mesh with 65 that in the housing 10^a, is carried by a rotatably supported shaft 16 extending into the latter through a side thereof, beyond which it has bearing in an adjacent bracket 70 17 on the window-frame and carries a crank-handle 16^a on its outer end. A transverse shaft or roller 18 extends along the under face of the top of the window-frame, and carries on its opposite ends similar miter-pinnions 13, like those hereinbefore named, 75 in the housings 10, respectively meshing with the other pinions 13 therein.

I prefer to form the roller 18 of telescoping sections to enable its length to be adjusted for different widths of window-frame, the section 18^a being shown solid and provided with a longitudinal groove 19, and the section 18^b being tubular to telescopically receive the solid section and provided with a stud 19^a to enter the groove 19 for 80 guidance in adjusting the length of the roller. The pinion on the tubular end of the roller 18 is on a stem 13^a pinned at α (Fig. 3) to the tube to turn with the roller.

The equipment thus described is primarily 85 intended for raising and lowering a shade 20 on a roller 20^a of the well-known Hartshorn type, and carried for the purpose by the spirals 12. Though if desired, as when such roller becomes impaired, or is 90 not used, or for any other reason, the shade may be fastened, for raising and lowering it, to the roller 18.

To adapt the spirals to carry a roller 20^a of the aforesaid type, I provide on each a 100 bracket, like that shown most clearly at 21 in Fig. 2, comprising a tube 21^a provided with an indentation forming a tooth 21^b to engage the spiral, the tube having an ear 21^c projecting from it through a longitudinal slot 23 in the spiral-sheathing tube, the ear of one of these brackets being provided with a slot 24 to receive and confine the flat pro-

jecting end-stud 25 on the roller, and that of the opposite bracket containing a hole, indicated at 24^a in Fig. 6, for journaling the stud 25^a projecting from the opposite roller-
5 end.

With a shade 20 supported as represented in Fig. 1, turning the handle 16^a in clockwise direction causes the rotating spirals to raise and in the opposite direction to lower 10 the roller 20^a with the shade to any desired position, since the gearing operates to rotate both spirals uniformly in relatively opposite directions owing to their being gear-connected by the roller 18; and in any position 15 to which the shade-roller 20^a is thus brought, the shade may be manipulated, in the usual manner when carried by the Harts-horn type of roller, to effect raising and lowering thereof to desired extent.

20 Of course, where the roller 20^a is dispensed with and the shade is suspended from the roller 18, the handle 16^a may be operated to lower the shade as well as to raise it.

I realize that considerable variation is 25 possible in the details of construction herein shown and described and I do not intend to limit my invention thereto except as pointed out in the appended claim, in which it is my intention to claim all the novelty inher-

ent in my invention as broadly as permissible by the state of the art. 30

I claim:

Window shade adjusting mechanism comprising a sheathing tube member disposable at the side of a window frame, a housing member surmounted on said tube member and having an attaching element extending therefrom, one of the members at the zone of contact having a bearing wall, a gear wheel disposed in said housing member and having a stub shaft journaled in said bearing wall and depending below the same into said tube member, a transverse shaft in driven relation to said gear wheel and journaled in said housing, a cap at the lower end of said tube member having an attaching element extending therefrom, a drive shaft extending exteriorly of the tube and journaled in the cap, a spiral shaft of rod material located within the tube member and fastened to the portions of the stub shaft and drive shaft disposed therein, a roller-supporting bracket having threaded engagement with said spiral shaft and operating means for said drive shaft located 45 exteriorly of the tube. 50

JAMES W. DAWSON. 55
